UNITED STATES PATENT OFFICE

WILLIAM K. KLEAVER, OF GRAND RAPIDS, MICHIGAN

DESIGN FOR A RADIO TABLE OR SIMILAR ARTICLE

Application filed March 12, 1932. Serial No. 43,168. Term of patent 3½ years.

To all whom it may concern:

Be it known that I, WILLIAM K. KLEAVER, a citizen of the United States, residing at Grand Rapids, in the county of Kent and State of Michigan, have invented a new, original, and ornamental Design for a Radio Table or Similar Article, of which the following is a specification, reference being had to the accompanying drawing, forming part thereof.

The figure upon the drawing is a perspective view of the article, showing my new design.

The rear of the design is substantially identical to the ends shown in the drawing.

I claim:

The ornamental design for a radio table or similar article, as shown and described.

WILLIAM K. KLEAVER.
